AUTOMOBILE DOOR LOCK KNOB

Alex Kraus, Los Angeles, Calif.
(1650 W. Rosecrans Ave., Gardena, Calif. 90249)

Filed May 31, 1968, Ser. No. 12,161

Term of patent 7 years

Int. Cl. D8—03

U.S. Cl. D8—113

FIG. 1.

FIG. 2.

FIG. 3.

FIG. 4.

FIGURE 1 is a side elevation view of the automobile door lock knob;

FIGURE 2 is a side elevational view of the automobile door lock knob, rotated 90° from the side elevation view of FIG. 1;

FIGURE 3 is a bottom end view of the automobile door lock knob; and

FIGURE 4 is a top end view of the automobile door lock knob.

I claim:

The ornamental design for an automobile door lock knob, substantially as shown.
